UNITED STATES PATENT OFFICE.

JAMES A. PIPKIN, OF WACO, TEXAS.

BOTTLE PROTECTOR.

Application filed April 18, 1925. Serial No. 24,073.

This invention relates generally to improvements in protectors for containers such as bottles, glasses, and similar articles, and more particularly to protectors of the type 5 that may be readily applied to such containers for the dual purpose of providing a cushioning base for the containers, and for catching and absorbing moisture of condensation, drippings, etc., which run down the 10 exterior surfaces of the container.

Experience has shown that in dispensing beverages such as soft drinks and the like, at soda fountains, soft drink stands, and roadside refreshment booths, considerable 15 annoyance and embarrassment has been experienced by both the proprietors and the patrons, due to the fact that the liquid refreshments dispensed are usually iced and served in glasses, bottles, or other containers 20 which, upon contact with the warmer air, condense the moisture therein, which collects upon the exterior surface of the containers in quantities sufficient to cause the same to trickle down the sides thereof in tiny 25 streams, and eventually to drop from the lower edge of the container onto the clothing of the party indulging in the refreshments. This is particularly true where soft drink beverages are served in the original 30 bottles and which, prior to being served, have been stored in a refrigerator or packed in crushed ice for the purpose of cooling the contents of the bottle, as is the usual practice at roadside refreshment booths, in which 35 case the bottle, when served, is actually dripping with moisture both from condensation and from contact with the ice bath. It has also been noted that, due to the insecure gripping surface afforded by wet glasses, 40 bottles or glasses of beverage are often accidentally dropped by slipping from the hands of the holder, with disastrous results, not only to the container itself, but to the clothing of people in the immediate vicinity.

With these facts in mind, the present invention has for its object the provision of a cup-shaped attachment for containers such as bottles, glasses, etc., used for dispensing cold drinks and beverages, which will cover 45 the bottom and surround the lower portion of the container and serve to absorb the

moisture on the outer surface thereof, as well as to provide a cushioning base for the container, whereby to substantially reduce the possibility of breakage of the container. 55

A further object of the invention is to so design the protector as to preclude the possibility of its being used as, or mistaken for a drinking vessel.

Another object of the invention is to provide a protector such as above described, which will be simple and economical to manufacture and use, but which will be thoroughly practicable and which will efficiently fulfill the purpose for which it was designed. 60 65

These and other objects will become apparent from the following description taken in connection with the accompanying drawings, in which—

Figure 1 is an elevation of a bottle with 70 the invention applied thereto.

Figure 2 is a perspective view of one form of the invention.

Figure 3 is a perspective view of a modified form of the invention. 75

Figure 4 is a fragmentary view of that form of the invention illustrated in Figure 3 applied to a container.

Figure 5 is an elevation of the invention applied to a drinking glass. 80

Referring more particularly to the drawings, in which like reference characters designate like parts throughout, 1 is a container in the form of a bottle such as is generally employed in bottling and dispensing soft 85 drinks, to which a protector 2, such as contemplated by the present invention, is applied. The protector comprises a flat bottom and a cup-shaped body portion 3 substantially cylindrical in form and designed 90 to cover the bottom and surround the lower portion of the container to which it is to be applied. The protector may be made of any suitable and inexpensive material, such as absorbent paper, blotting paper, or the like, 95 and may be molded or otherwise formed in various sizes and shapes to be determined by the configuration and size of the container with which it is to be used.

The protector 2, while being similar in 100 size and shape to an ordinary paper drinking cup, is in no way adapted for such use,

due to the fact that it is made of absorbent material, and, as such, possesses no water resisting qualities, but, on the contrary, has a great affinity therefor. In order, therefore, to preclude the possibility of it being mistaken or used for a drinking cup, the cylindrical body wall thereof is apertured at 4 and provided at its upper edge with a plurality of serrations 5, it being noted that 10 the apertures 4 not only indicate that the article is not a drinking vessel, but also provide means for the ready escape of air entrapped in the protector when being applied to a container; while the serrations 5 not 15 only present an edge decidedly repugnant to the idea of using the protector as a drinking vessel, but they also serve to greatly increase the absorbent surface available for the purpose of encountering the moisture and drippings running down the sides of 20 the container.

In Figure 3 a slightly modified form of the invention is illustrated, wherein the upper edge 6 of the protector is rolled or beaded and provided with an expansible contracted portion as at 7, whereby the protector will hug the walls of a container and, due to said expansible portion, will be able to accommodate itself to slight variations in the size 30 of the container. This feature is clearly illustrated in Figure 4, wherein a protector such as illustrated in Figure 3 is shown applied to a container of slightly increased size, the rolled edge 6 and contracted portion 35 7 having expanded to snugly fit the walls of the container. It is to be noted that in this modification the rolled or beaded edge 6 presents an enlarged absorbent surface to the moisture-laden walls of the container, 40 corresponding to the serrated edge 5 of that form of the invention illustrated in Figure 2.

The protector may be made of paper stock of various colors to provide an article of 45 pleasing appearance, and should be of a suitable thickness to afford not only a sufficient amount of stock to absorb the necessary quantity of moisture from the container walls, but also to provide a cushioned base 50 for the container. If desired, the body of the protector may contain certain advertising matter, such as indicated at 8, it being apparent that the particular use to which 55 the protector is put makes it an unusually valuable medium of advertising.

From the foregoing description it is apparent that a protector for bottles and drinking vessels has been provided which is simple in construction, economical to manufacture, 60 and one that may be readily applied to a container, and which, when so applied, will not only quickly and completely absorb all moisture and drippings upon the outer surface thereof, but will furthermore provide a cushioned base for the container. Further-

more, the protector is such that it provides an ideal gripping surface for holding the container while partaking of its contents, and thus all possibility of accidentally dropping the container is substantially precluded. 70

It is to be noted that, while several preferred modifications of the invention have been herein illustrated and described, such illustrations and description have been for the purpose of example only, and not as 75 defining the limits of the invention, which are to be determined by the scope of the appended claims.

Having thus described my invention what I claim as new is:

1. A protector for use on drinking vessels comprising a cup having a body portion designed to fit snugly against and surround at least the lower portion of the periphery of the body of the vessel, said body portion having an open top and a bottom closing the lower end of the body portion and designed to fit snugly against the bottom of the vessel, said body portion and the bottom of said cup being constructed of moisture absorbent material, the upper end of the body portion being shaped to present an edge area greater than the cross sectional area of the body portion to increase the moisture absorbent capacity of the upper end, said upper end being fitted snugly against and flatly engaging the periphery of the body of the vessel throughout the entire linear extent of the edge area of the upper end. 95

2. A protector for use on drinking vessels 100 comprising a cup having a body portion designed to fit snugly against and surround at least the lower portion of the periphery of the body of the vessel, said body portion having an open top and a bottom closing the lower end of the body portion and designed to fit snugly against the bottom of the vessel, said body portion and the bottom of the cup being constructed of moisture absorbent material, the upper end of the body portion being serrated to present an edge area greater than the cross sectional area of the body portion to increase the moisture absorbent capacity of the upper end, said upper end being fitted snugly against and flatly engaging the periphery of the body of the vessel throughout the entire linear extent of the edge area of the upper end. 110

3. A protector for use on drinking vessels 115 comprising a cup having a body portion designed to fit snugly against and surround at least the lower portion of the periphery of the body of the vessel, said body portion having an open top and a bottom closing the lower end of the body portion and designed to fit snugly against the bottom of the vessel, said body portion and the bottom of said cup being constructed of moisture absorbent material, the body portion of the cup having 120 openings therein slightly above the closed 125

bottom of the cup to permit the escape of air entrapped in the cup when being applied to a vessel.

4. A protector for liquid containers comprising a cup of water-absorbing material designed to envelop the lower portion of a container, said cup being provided with a

cushioned bottom, a serrated upper edge, and a plurality of apertures in the walls thereof whereby to permit the escape of air ¹⁰ entrapped in the cup when being applied to a container.

In testimony whereof I affix my signature.
JAMES A. PIPKIN.
